UNITED STATES PATENT OFFICE.

JOSEPH P. FILLINGHAM, OF BATTLECREEK, MICHIGAN, ASSIGNOR OF NINE-TENTHS TO RICHARD R. HICKS AND EUGENE L. MARKEY, OF BATTLECREEK, MICHIGAN.

AUTOMATIC GOVERNOR FOR FLUID-COMPRESSORS.

SPECIFICATION forming part of Letters Patent No. 707,687, dated August 26, 1902.

Application filed October 12, 1901. Serial No. 78,489. (No model.)

To all whom it may concern:

Be it known that I, JOSEPH P. FILLINGHAM, of Battlecreek, in the county of Calhoun and State of Michigan, have invented certain new and useful Improvements in Automatic Governors for Fluid-Compressors; and I hereby declare that the following is a full, clear, and exact description thereof, reference being had to the accompanying drawings, which

10 form part of this specification.

This invention is an improved automatic governor for fluid-compressors particularly designed for use in connection with air-brake apparatus for street-railway cars, in which 15 apparatus the air is compressed into suitable reservoirs by means of air-pumps actuated directly or indirectly from the car-axles; and the object of the invention is to produce a simple and effective form of governor by 20 which the pump or compressor will be relieved from duty, although continuing its motions, when the pressure of air in the storage-reservoir reaches a predetermined limit and by which the effective operation of the 25 pump will be resumed when the pressure in the reservoir falls below the desired limit.

Another object of the invention is to connect the relief-port with the crank-case, so 30 that when the pump is working idly the air will be circulated between the pump and crank-case without going to the exterior atmosphere, thus reducing the amount of dust and grit which would otherwise be drawn into the apparatus if the relief-port vented 35 into the open. Furthermore, by such construction any oil sucked into the pump or relief-valves can be driven back into the crank-case without waste, and the disagreeable hissing noise of the escaping air is prevented.

40 A further object of the invention is to enable the pump to be relieved of duty without disturbing either its inlet or outlet valves—that is, neither of such valves must be held open or unseated during the ineffective or 45 non-compressing strokes of the pump.

My invention is embodied in the peculiar novel construction and arrangement of parts 50 hereinafter described whereby the foregoing objects are attained, and the features thereof wherein the invention consists and upon

which protection is desired are summarized in the claims following the detailed description of said governor, as illustrated in the accompanying drawings, in which—

Figure 1 is a top plan view of a simple form 55 of air-compressor adapted to be operated from a car-axle and having my governor applied and partly in section. Fig. 2 is a side view partly in section. Fig. 3 is an end view of Fig. 1, showing the location of the 60 governor. Fig. 4 is an enlarged vertical section through the governor on line 4 4, Fig. 5. Fig. 5 is a plan view, partly broken, of the governor combined in one casing with the main compressor-valves. Fig. 6 is a vertical 65 section on line 6 6, Fig. 5. Fig. 7 is a detail view of the governor-valve G.

The air pump or compressor shown in drawings comprises a cylinder A, closed at its outer end and connected at its inner end 70 to a crank-case B, and within the cylinder is a piston A', connected by a pitman a to a crank-gear B' within case B, said gear being driven by a pinion c from one of the car-axles C. These parts are merely conventional 75 illustrated in drawings, as any well-known or preferred construction thereof may be employed.

Attached to the cylinder A, near the rear side thereof, is the valve-chamber D, which 80 has an inlet d at bottom controlled by a valve D', and at center, above valve D', is a port D², which opens directly into the rear end of the pump. Above port D² is the outlet-port d', which is closed by a valve D³, setlike valve 85 D'; but owing to the intermediate connection of port D² the valves D' D² will be unseated alternately by the inrush and outrush of air to and from port D² in the effective working operation of the pump, in which the inward 90 stroke of piston A' sucks air through ports d D² into the cylinder, (valve D³ remaining seated,) while on the outstroke of the piston A' air is forced through ports D² d' to the reservoir-chamber S, a pipe or port d² connecting port d' above the valve D³ with said reservoir. 95

The relief-valve chamber E may be located at any convenient point. As shown in Figs. 1 to 3, it is located somewhat remote from the 100

pump-valve chamber D, the port A² leading through the wall of the cylinder-head to said chamber E, which is attached to the cylinder-head near its lower side, while valve-chamber D is attached to the side of cylinder at a point above casing E. As shown in Figs. 4, 5, and 6, the relief-valve chamber E is just beside the pump-valve chamber D. The relative location of the valve-chambers D E is a matter of choice and does not materially affect their coöperative relation or structure.

Within the relief-valve chamber E is a double-headed relief-valve e e', having a cup-leather on each end and a central annular channel e², adapted to register with the relief-port A² (or d²) when the valve is in its uppermost position, and when the valve is in its lowermost position the relief-port is closed by part e of the relief-valve. As shown in Fig. 2, the relief-port A² enters chamber E near its center and leads therefrom directly through the cylinder-head into the working chamber of the pump. As shown in Fig. 6, the relief-port d² opens into the chamber E near its center and extends directly through the walls of chambers D E and communicates with the chamber D intermediate ports d d'. Said port d² therefore constantly communicates with the working chamber of the pump through port D². Thus in both cases the relief-port is always constantly open to the working chamber and is controlled by the position of the relief-valves e e' in the chamber E.

In the wall of chamber E are two ports f f', leading from opposite ends of said chamber and opening near each other into the governor-valve chamber F, which is parallel with and beside chamber E and contains the piston H, upon the stem h of which the governor-valve G is secured, which controls the admission of air to and from chamber E. Piston H is closely fitted in the chamber F, below governor-valve G, and is pressed upwardly by means of a helical expansion-spring I, contained within a threaded bushing F', screwed into the lower end of chamber F and closed by an adjusting-nut F², which is locked by a jam-nut F³, as shown. The inner end of bushing F' serves as a stop to limit the downward movement of piston H and valve G. The governor-valve G is segmental in cross-section, so that it will not obstruct passage of air into and from chamber F above piston H, and it is confined on stem h between the piston H and a spider H' on the upper end of rod h, being prevented from rotating on the stem by a pin g engaging a notch in piston H, and the latter is kept from rotating by a pin h' engaging a slot in stem h.

In the walls of chamber F are two independent ports i i', which respectively open into said chamber near the mouths of the ports f f', as shown, ports f i f' i' being controlled by the valve G, which has a central passage g³, opening into the valve-chamber F, and an upper and a lower pocket g' g', re-

spectively adapted to establish communication between ports f i when the governor-valve G is lowered or between ports f' i' when the governor-valve G is raised, and when the governor-valve G is lowered passage g³ establishes communication between the air-space in the upper part of chamber F and the lower part of chamber E through port f', and when the governor-valve G is raised its passage g³ establishes communication between the upper parts of chambers E and F through the port f.

The upper part of chamber F is continually filled with compressed air from the reservoir S through the connecting-passage d⁴, which leads directly or indirectly from chamber D above valve D³ to chamber F, according to the relative locations of said chambers.

Relief-chamber E has an outlet-port E², which may communicate with the atmosphere, as in Fig. 6, if desired; but I preferably connect this port by a pipe or passage A³, leading through the wall of the cylinder A, with the interior of the crank-case B, so that when the pump is working idly the air will be impelled back and forth between the crank-casing and pump-chamber, in which case the disagreeable noise incident to the rapid passage of air through a small open port is obviated, less dust gets into the working cylinder, and consequently into the working parts, than occurs where the relief-ports communicate directly with the atmosphere, and any oil which may get into the working cylinder or relief-valve chamber and ports will be expelled into the crank-chamber.

For convenience in construction port d may be formed in a tubular plug D⁵, screwed into the lower end of chamber D, and the upper end of said chamber may be closed by a removable screw-cap D⁶. In like manner the ends of chamber E may be closed by removable screw-caps E⁵ E⁶, and the upper end of chamber F may be closed by a removable screw-cap F⁶, affording a cheap construction and permitting easy access to working parts.

Operation: So long as the pressure of air in the reservoir S (and therefore in ports d³ d⁴ and air-space of chamber F) does not exceed the predetermined limit the parts will maintain the position indicated in Figs. 4 and 6, spring I holding piston H and governor-valve G raised against pressure of the air in chamber F, so that port f is in communication with the chamber F through passage g³, while port f' communicates with the atmosphere through pocket g' and port i', in which position the air-pressure holds the relief-valve in its lowermost position and relief-ports d² (or A²) and E² are closed and the pump continues to compress air into the reservoir. As soon as the pressure rises above the desired point the air overcomes the resistance of spring I and forces piston H and governor-valve G downward, thereby bringing passage g³ into register with port f', so that air enters chamber E below valve e' from chamber F, and at the same time port f is brought into

communication with the atmosphere, (through pocket g and port i .) whereupon the air forces the relief-valve e upward, establishing communication through channel e^2 between ports d^2 (or A^2) and E^2 , so that the pump ceases to act effectively and air is merely sucked back and forth through ports $A^3 E^2 A^2$ between the crank-chamber and working chamber of pump, (in the arrangement shown in Figs. 1 to 3,) or the air will be merely circulated idly through ports $E^2 d^2 D^2$ between the atmosphere and the working cylinder, (in the arrangement shown in Figs. 4 and 6.) In either arrangement it will be noted that the main pump-valves $D' D^3$ become inoperative and remain seated. If the pressure in reservoir S falls below the desired point, spring I overcomes the air-pressure in the governor-valve chamber F and raises piston H and governor-valve G , thereby reestablishing communication between port f' and the atmosphere and between port f and the interior of chamber F , so that the relief-valve is driven back to lowermost position and the relief-port (d^2 or A^2) is closed, whereupon the compression of air is immediately resumed by the pump.

Having thus described my invention, what I therefore claim as new, and desire to secure by Letters Patent thereon, is—

1. The combination of the pump-chamber, the relief-port communicating therewith, and with the atmosphere, a relief-valve chamber into which said port opens, and a relief-valve in said chamber, adapted to close said relief-port in one position and open same in another position; with a governor-valve chamber, a passage for admitting air which has been compressed by the pump into one end of said governor-valve chamber, a governor-valve operated one way by air-pressure, a spring for forcing said governor-valve in the other direction, adjoining pairs of ports leading respectively from the governor-valve chamber to the atmosphere, and to opposite ends of the relief-valve chamber, said governor-valve being adapted to establish communication through said ports between one end of the relief-valve chamber and the governor-valve chamber, and between the other end of the relief-valve chamber and the atmosphere, or vice versa, all substantially as and for the purpose described.

2. The combination of the pump, the relief-valve chamber, the valve therein, the adjoining governor-valve chamber, the piston therein, a spring for moving said piston in one direction, and means for admitting air which has been compressed by the pump into said chamber to move the piston against the spring, air-ports opening near their adjoining ends into the air-space of the governor-valve chamber, and at their other ends into opposite ends of the relief-valve chamber, and exhaust or venting ports adjacent to the air-ports and respectively opening at one end into the air-space of the governor-valve cham-

ber near the mouths of the air-ports and at their other ends into the atmosphere; with a governor-valve in the governor-valve chamber, operated by the piston therein, having a central passage communicating with the air-space of the governor-valve chamber and adapted to register with either of the said air-ports, said governor-valve also having two pockets respectively adapted to alternately establish communication between the respective air-ports and the related venting-ports, substantially as and for the purpose set forth.

3. The combination of the pump, the relief-valve chamber communicating therewith, the double-ended relief-valve in said chamber, and an outlet-port from said chamber communicating with the atmosphere; with the governor-valve chamber beside the relief-valve chamber, a passage for admitting air which has been compressed by the pump into said governor-valve chamber, air-ports leading from the governor-valve chamber to the opposite ends of the relief-valve chamber, and two vent-ports adjacent to the air-ports leading from said governor-valve chamber to the atmosphere; with the slide-valve having passage g^3 , communicating with the air-space in the governor-chamber, and pockets g, g' respectively adapted to establish communication between adjacent air and vent ports, a piston carrying said slide-valve, and an adjustable spring for holding the piston against the air-pressure, substantially as and for the purpose described.

4. The combination of an air-pump, an air-storing reservoir communicating therewith, and the main air inlet and outlet valves; with a relief-valve chamber adjacent to said valves, ports connecting the same with the pump and with the atmosphere, a relief-valve in said chamber adapted to normally close said ports, a governor-valve chamber communicating at one end with the reservoir; a piston in said governor-valve chamber adapted to be depressed by the pressure of the air which has been compressed by the pump, a spring for raising said piston opposite ports leading from the air-space of the governor-valve chamber to the opposite ends of the relief-valve chamber above and below the relief-valve; vent-ports leading from the governor-valve chamber to the atmosphere, a governor-valve in said governor-valve chamber actuated by the piston, and adapted to establish communication between either relief-valve port and the governor-valve chamber, and the other relief-valve port and the atmosphere so as to cause the compressed air to actuate the relief-valve and render the pump effective or ineffective in operation, substantially as described.

5. The combination of the working cylinder or pump-cylinder, its inlet and outlet valves, a relief-port communicating with said cylinder intermediate the valves, a relief-valve, a governor-valve chamber beside the relief-valve casing, a piston therein, operated one way by the air which has been compressed

by the pump; a spring for forcing said piston in the opposite direction; opposite air-ports leading from the air-chamber in the governor-valve casing to the relief-valve casing and 5 opening thereinto on opposite sides of the relief-valve, adjacent vent-ports in the walls of the governor-valve chamber, and a governor-valve operated by the piston controlling said opposite air-ports and adjacent vent-ports, 10 and means for venting one end of the governor-valve casing when air is admitted to the opposite end thereof.

6. The combination of the pump-cylinder, the pump-valve chamber, the adjacent valves 15 therein, the relief-valve chamber, a relief-port leading from the pump-valve chamber between the valve therein to the atmosphere, a relief-valve adapted to close said relief-port in one position and open it in another position; 20 a governor-valve chamber, air-ports leading from the governor-valve chamber to the relief-valve chamber and opening therein, at opposite sides of the relief-valve, and vent-ports leading from the governor-valve 25 chamber to the atmosphere, a slide-valve in the governor-valve chamber for controlling said air and vent ports, a piston connected to and actuating said slide-valve, a passage connecting the pump-valve chamber with the 30 governor-valve chamber to admit air which has been compressed by the pump into the governor-valve chamber above the piston, and a spring for holding the piston against the air-pressure, substantially as described.

35. 7. The combination of the pump-cylinder, the crank-case, the relief-valve chamber, a port leading from said chamber to the pump, and a second port leading from said relief-valve chamber to the crank-case; with a relief-valve in said chamber, and means controlled by the air-pressure whereby said relief-valve is opened when the pressure rises above the desired degree, substantially as described.

45. 8. The combination of the pump, the pump-valves at one side thereof, the compressed-air reservoir, and the crank-case, the relief-port for the pump; a relief-valve chamber communicating therewith, a port or passage 50 connecting said relief-valve chamber with the crank-case, a relief-valve in said chamber, a governor-valve chamber, ports connecting the governor-valve chamber with the relief-valve chamber, and ports leading from the

governor-valve chamber to the atmosphere; 55 a valve in the governor-valve chamber controlling all ports thereof, a spring for holding the governor-valve against the air-pressure, and an air-channel leading from the reservoir to the governor-valve chamber above the valve therein, all substantially as and for the purpose described.

9. The combination of the pump-cylinder, the crank-case, the relief-valve chamber, a port leading from said chamber to the pump, 65 another port leading through said cylinder-wall to the crank-case, a relief-valve in said chamber adapted to close said ports in one position and open them in another position; a governor-valve chamber beside the relief- 70 valve chamber, ports leading from the governor-valve chamber to the relief-valve chamber and opening therein at opposite sides of the relief-valve, a slide-valve in the governor-valve chamber for controlling said ports, a 75 piston connected to and actuating said slide-valve, a passage for admitting compressed air into the governor-valve chamber above the piston, and a spring for holding the piston against the air-pressure, substantially as 80 and for the purpose described.

10. The combination of the pump, its crank-case, the pump-valves at one side of the cylinder, the compressed-air reservoir, a relief-valve chamber directly communicating with 85 the pump, a port or passage leading from said relief-valve chamber to the crank-case, a relief-valve in said chamber, a governor-valve chamber beside the relief-valve chamber, ports connecting the governor-valve chamber with opposite ends of the relief-valve chamber, and ports leading from the governor-valve chamber to the atmosphere, a slide-valve in the governor-valve chamber, controlling all ports thereof; a piston in said 90 governor-valve chamber actuating said slide-valve, a spring for holding the piston against the air-pressure, and an air-passage leading from the reservoir to the governor-valve chamber above the piston, all substantially 95 100 as and for purpose set forth.

In testimony that I claim the foregoing as my own I affix my signature in presence of two witnesses.

JOSEPH P. FILLINGHAM.
